UNITED STATES PATENT OFFICE.

LA MOTTE C. ATWOOD, OF ST. LOUIS, MISSOURI, ASSIGNOR TO THE ATWOOD ELECTRIC COMPANY, OF SAME PLACE.

ELECTRIC-ARC LAMP.

SPECIFICATION forming part of Letters Patent No. 448,107, dated March 10, 1891.

Application filed October 28, 1890. Serial No. 369,547. (No model.)

To all whom it may concern:

Be it known that I, LA MOTTE C. ATWOOD, of the city of St. Louis, in the State of Missouri, have invented a certain new and useful Improvement in Electric-Arc Lamps, of which the following is a full, clear, and exact description, reference being had to the accompanying drawings, forming part of this specification.

10 My invention relates to certain improvements in that class of electric-arc lamps having a motor for moving the carbons as they are consumed; and my invention consists in features hereinafter fully described, and 15 pointed out in the claim.

Figure I is an elevation illustrative of my invention. Fig. II is an enlarged top or plan view. Fig. III is an enlarged view of the circuit-distributing switches. Fig. IV is an 20 enlarged section of the automatic clutch. Fig. V is a side elevation of the lamp. Fig. VI is a diagram illustrating the arrangement of the wires, &c.

Referring to the drawings, 1 represents the 25 base of the lamp, which may be supported on legs 2. Over the base 1 is a plate 3, connected to the base by rods 4. Between the base and plate are located the main magnets 5, through which the circuit passes to the 30 carbons and shunt-magnets 6. On top of the plate 3 is the motor 7, an armature 8 of the magnets 5, and an armature 9 of the magnets 6.

10 represents a tube or rod fitting in sockets or openings made in the base 1 and plate 35 3. It has an arm 11 at its upper end, which carries a clamp 12 for holding the upper carbon 13. On one side of the rod 10 there is a rack 14, engaged by a pinion 15, secured 40 to a shaft 16. The shaft is journaled in the upper ends of standards 17, secured to the plate 3.

18 represents a tube or rod fitting in sockets or openings made in the plate 3 and base 45 1. This rod or tube has an arm 19 on its lower end, which carries a clamp 20 for holding the lower carbon 21. On one side of this rod there is a rack 22, engaged by a pinion 23 on the shaft 16. The turning of the shaft

16 causes the carbons to be moved to or from 50 each other, (according to which way the shaft is turned,) and for the purpose of causing the upper carbon to be moved faster than the lower one (on account of its more rapid consumption) the pinion 15 is made larger than 55 the pinion 23.

24 represents a worm-wheel loosely mounted on the shaft 16 and which engages a worm 25 on a shaft 26, arranged at right angles to the shaft 16 and journaled in standards 60 27, extending upward from the plate 3 or from a cross-piece 28, reaching from one of the standards 17 to the other. (See Fig. II.) On the shaft 26 there is also secured a worm-wheel 29, which engages a worm 30 on 65 the extended end of a shaft 31 of the motor 7.

32 represents the field-magnets, located over the motor 7.

33 represents a sliding clutch mounted on the shaft 16, so as to have end movement 70 thereon, but forced to turn therewith by a feather-and-groove or other suitable connection. A feather is shown at 34, Fig. II. This clutch has pins 35 to engage holes 36 in the face of the worm-wheel 24. The clutch has 75 sufficient end movement on the shaft to permit the pins to be disengaged from the holes, as shown in Figs. I and II.

37 represents a lever pivoted as shown at 80 38, Fig. I, and the upper end of which is forked or bifurcated to embrace the clutch and has pins 39 entering a circumferential groove 40 in the clutch. The lower end of the lever is connected by a link 41 to the inner end of a bell-crank lever 42, pivoted at 43, and the 85 outer end of which is connected by a link 44 to the outer edge of the armature 8. The inner edge of the armature 8 is hinged to the plate 3, as shown at 45, Fig. I. It will be understood that when the armature 8 is attracted by the magnets 5 the clutch through 90 means of the described connection will be forced into engagement with the worm-wheel 24, and thus cause the shaft 26 to be turned by the motor through means of the described 95 connection. When the magnets release the armature, the clutch is drawn out of engagement with the worm-wheel by a spring 46,

- connected to the lower end of the lever 37. The armature 9 is hinged to the plate 3, as shown at 47, Fig. II. Its free end is held in its upper position, when not attracted by the magnets 6, by a spring 48, (see Fig. V,) on the upper end of which is secured a threaded rod 49, which passes through a plate 50 on the upper end of a standard 51, mounted on the plate 3. (See Fig. I.)
- 10 On the rod 49 is a thumb nut 52 above the plate 50, by which the tension of the spring 48 may be regulated. The thumb-nut may be held from accidental turning by a pawl 53, engaging notches 54 on the thumb-nut.
- 15 On the free end of the armature 9 there is a projection 55, having an upper contact-point 56 and a lower contact-point 57, and another projection 58, having an upper contact-point 59 and a lower contact-point 60.
- 20 The projections 55 and 58 are insulated from the armature, preferably, by means of a piece of hard rubber 61, by which they are secured to the armature. (See Fig. V.)
- 25 62 represents an upper plate, against which the contact-point 56 may impinge; 63, an intermediate plate, against the upper surface of which the contact-point 57 may impinge and against the lower surface of which the contact-point 59 may impinge, and 64 a lower plate, against which the contact-point 60 may impinge. The plates 62, 63, and 64 are all secured to and supported by a standard 65 on the plate 3, the plates being insulated from the standard, or the standard may
- 30 be composed of some non-conductive material. The movement of the armature 9 by the magnets 6 in one direction and by the spring 48 in the other direction causes the contact-points to impinge their respective plates.
- 40 I will now describe the arrangement of the wires and the operation of the lamp.
- 50 70 represents a wire leading from the electric supply to the magnets 5.
- 45 71 represents a wire leading from the magnets 5 to the upper-carbon clamp 12, and 72 a wire leading from the lower-carbon clamp 20. The current passing through the magnets 5 pulls the armature 8 down and engages the clutch 33 with the worm-wheel 24.
- 55 73 represents a wire leading from a branch 70^a of the wire 70 to the intermediate plate 63, through which a portion of the current passes from the wire 70 to the plate 63, thence through the contact-point 59, thence through a wire 74, thence to the field-magnets of the motor, thence through a wire 75 to contact-point 56, thence through the upper plate 62, thence through a wire 76, thence to the brush 60 77 of the commutator 78 of the motor, thence through the armature 79 of the motor, thence from the armature of the motor through the brush 80 of the commutator of the motor, and thence through a wire 81 to the wire 71 of the upper carbon. This current causes the

motor to run backward and through the described connection causes the carbons to be moved apart to produce the arc.

82 represents a wire leading from the branch 70^a of the wire 70 and through which a current passes to the shunt-magnets, thence through a wire 83 to the wire 72 of the lower carbon. The shunt-magnets are of high resistance, and the amount of current passing through them depends upon the length 75 of the arc of the carbons. As soon as the resistance is sufficient the magnets draw the armature 9 down, breaking the contact between the point 56 and the upper plate 62 and between the point 59 and the under side 80 of the plate 63, cutting off the current to the motor, which ceases to move. As the carbons are consumed and the resistance increased, the shunt-magnets draw the armature 9 down farther until the contact-point 57 comes 85 against the upper side of the plate 63 and the point 60 comes against the lower plate 64, when the motor will be turned forward to feed the carbons together by the current passing from wire 73 through the plate 63, 90 the contact-point 57, and through the wire 75, returning through the wire 74 and to the armature of the motor through the wire 76. As soon as the carbons have been fed sufficiently and the resistance decreased the armature 9 rises, breaking the contact between the points 57 and 60 and their plates 63 and 64, when the current to the motor will be cut off again and it will cease to turn until the carbons are consumed sufficiently to 100 create the necessary resistance to cause the armature to be drawn down again and start the motor forward to feed the carbons again, and thus the operation goes on continuously, the current to the motor being made and 105 broken as the resistance of the carbons increases and diminishes.

90 represents a plate beneath the plate 64, and with which the branch wire 70^a from the wire 70 connects, and beneath the free end 110 of which is a contact-point 92, from which a wire 93 extends to the wire 72. Now, in case anything should happen to the motor, so that it would not start when the armature 9 has been drawn down, as explained, the further 115 downward movement of the armature will bring an insulated projection 94 down upon the plate 90 and force its free end against the point 92, thus establishing a contact between the wires 91 and 93, through which the 120 current will pass around the lamp. As soon as this takes place the magnets 5 will release the armature 8, when the clutch will be disengaged and the carbons will drop together. The armature 9 will then be released, the 125 current will pass to the main magnets 5 again, the clutch will be again engaged, the motor will be turned backward again to form the arc, and the parts will all proceed to perform their functions.

I claim as my invention—

In an electric-arc lamp, the combination of carbon-supporting rods, a motor, a train of gearing located between the motor and rods and containing an automatic clutch by which the gearing is thrown into and out of action, a magnet and armature, a spring-actuated pivoted lever connected to said clutch, a piv-

oted bell-crank lever, a link connecting said levers, and a link connecting said bell-crank lever to said armature, substantially as and for the purpose set forth.

LA MOTTE C. ATWOOD.
